UNITED STATES PATENT OFFICE.

EDWIN V. BABBITT, OF FAIRHAVEN, MASSACHUSETTS.

SOLDIER TOY.

Application filed June 8, 1926. Serial No. 114,483.

This invention relates to a toy simulating a marching soldier mounted on a support and having pivoted legs, the toy including means for moving the legs relative to the body to produce the effect of marching. A toy of this character is shown by my application filed July 31, 1925, Serial No. 47,274, and by a later application filed concurrently herewith.

The object of the present invention is to provide a toy soldier accoutred to simulate a continental soldier wearing a cocked hat and preferably a peruke with a queue. The invention is embodied in the improvements hereinafter described relating to the head and hat portions of a toy soldier.

Of the accompanying drawing,—

Fig. 1 is a side view of a toy soldier and supporting means therefor;

Figs. 2, 3 and 4 are respectively front, side, and top views showing the head and hat portions in which my improvements are embodied;

Fig. 5 is a section on line 5—5 of Fig. 4;

Fig. 6 is a plan view of the blank of flexible sheet material constituting one of the sections of the hat shown by the preceding figures.

The same reference characters designate the same parts in all the figures wherever they occur.

The body 12, the head 13, and the legs 14 of the toy soldier shown by Fig. 1, may be constructed as shown by my former applications above mentioned, and the body may be fixed to a standard 15 which in turn is fixed to a platform 16 having wheels 17. The legs may be pivoted to the lower portion of the body, and means actuated by the rotation of one pair of wheels may be provided for oscillating the legs as shown by my former applications. I do not show said means in this application, as the present invention does not relate thereto. The head 13 is preferably spherical and fixed to the body 12. The head is provided with a cocked hat composed of sections 19 and 20, adapted to be assembled on the head. The section 19, called the brim section, is of flexible sheet material, preferably thin leather, and originally of circular form, as

shown by Fig. 6. The central portion of this section is superimposed on the top portion of the head 13, the section being formed to extend outwardly from the head. The section 20, called the crown section, is of rigid material, preferably wood, and has a convex upper end. The lower end of the crown section is superimposed on the central portion of the brim section. A headed fastener 21, preferably a brass nail, is driven through the crown section and the brim section into the head 13, as shown by Fig. 5, so that the sections are fixed to the head, the central portion of the brim section being clamped between the crown section and the top of the head. The head of the fastener 21 may be enlarged to ornament the crown section.

The marginal portion of the brim section is turned upward, preferably at three places, against the upper portion of the crown section, and is united to the latter by fasteners 22, preferably small nails or tacks. This operation gives the brim section the appearance of the brim of a three cornered cocked hat. One of the fasteners 22 is preferably provided with an enlarged head 22^a simulating a cockade at one side of the brim.

To increase the resemblance of the figure 80 to a continental soldier, I provide a peruke 24 which may be provided with a queue 25. The peruke may be comprised of cotton batting and a portion of it is interposed between the head 13 and the central portion of the 85 brim section, as shown by Fig. 5. The brim and crown sections therefore protect and confine the top portion of the peruke, which may be cemented to the head.

I claim:

1. A toy soldier comprising a head and a sectional cocked hat including a brim section of sheet material superimposed on the top portion of the head, a rigid crown section superimposed on the brim section and secured to the head by a headed fastening member extending through the crown and the brim sections into the head, so that the central portion of the brim section is clamped between the head and the crown section, the marginal portion of the brim section being turned upward and portions thereof being

secured to the crown section, so that the crown section simulates the crown, and the brim section the brim of a cocked hat.

2. A toy soldier as specified by claim 1, the marginal portion of the brim section being secured to the crown section by fasteners, one of which has a head simulating a cockade.

3. A toy soldier as specified by claim 1, comprising also a peruke, a portion of which is interposed between the head and the brim section.

In testimony whereof I have affixed my signature.

EDWIN V. BABBITT.
